UNITED STATES PATENT OFFICE.

CHARLES A. WILKINSON, OF WORCESTER, MASSACHUSETTS.

APPARATUS FOR CHARGING AND DISPENSING LIQUIDS.

SPECIFICATION forming part of Letters Patent No. 699,047, dated April 29, 1902.

Application filed April 6, 1901. Serial No. 54,631. (No model.)

To all whom it may concern:

Be it known that I, CHARLES A. WILKINSON, a citizen of the United States, and a resident of Worcester, in the county of Worcester and 5 State of Massachusetts, have invented a new and Improved Apparatus for Charging and Dispensing Liquids, of which the following is a full, clear, and exact description.

This invention relates to an apparatus designed especially for use on soda-water stands to constitute the so-called "soda-water fountain." By means of my apparatus the water is charged with the gas employed as fast as it is used, a mixing and charging device being 15 comprised in the apparatus. After the water is charged it is led to a reservoir fitted with a gage, so that the height of the water in the reservoir may be readily discerned, the reservoir being also fitted with a siphon or 20 siphons for drawing off the charged liquid. The advantages of such an arrangement will be obvious to persons skilled in the art.

This specification is a specific description of one form of the invention, while the claims 25 are definitions of the actual scope thereof.

Reference is to be had to the accompanying drawings, forming a part of this specification, in which similar characters of reference indicate corresponding parts in both the views.

30 Figure 1 is a perspective view of the apparatus, and Fig. 2 is a vertical section thereof.

a indicates a suitable box or casing which may be lined with metal, so as to carry ice crushed or in other form, as desired.

35 *b* indicates the water-supply pipe, and *c* the gas-supply pipe. These pipes may be coiled within the casing *a*, so that they will be kept cool by the ice therein.

40 *c'* indicates a valve which is supported within the casing *a* by a bracket *a'* and the stem *c'* of which passes through the casing *a* and has attached thereto a finger-wheel *c''*. With this finger-wheel works a pointer *c'*, and the finger-wheel may be graduated on its 45 periphery, so that the operator may know

just to what extent the valve *c'* has been opened. This valve commands the flow of gas from the pipe *c*. A continuation *c''* of the pipe *c* leads to an injector-nozzle *d*, which is 50 arranged in the dome *d'* of the mixing-chamber *d*. Leading to the dome *d'* is an extension *b'* of the water-pipe *b*. The water-pipe

b is commanded by a valve *b'*, the stem *b''* of which passes out through the front wall of the casing *a* and is provided with a suitable 55 finger-wheel.

e represents the reservoir for the charged or carbonated water, and this reservoir has a perforated top portion *e'*, which is covered by the mixing-chamber *d*, so that the water 60 may pass from the mixing-chamber into the reservoir.

e'' indicate siphon-pipes, which pass from the reservoir *e* through the top thereof and out through the front wall of the casing, 65 where suitable cocks *e'''* are provided.

f indicates a gage which shows the height of the water within the reservoir, and *g* indicates a gage showing the pressure in the mixing-chamber. 70

Now with this arrangement, there being a pressure of water in the pipe *b* and of gas in the pipe *c*, the valve *c'* may be opened and the gas injected into the dome *d'*. Then by turning on the water the water will be broken up 75 into fine particles and become charged with gas. The mixture then passes into the chamber *d*, where the mixing process is still carried on, and finally the aerated or carbonated water passes into the reservoir, where it is 80 held under a certain pressure, as will be understood. By operating the cocks *e'''* this water may be drawn off at will. The gage *f* will show the height of the water in the reservoir and will show when this water needs replenishing. If desired, a pressure-gage may be 85 connected with the mixing-chamber *d* to show the gas-pressure therein. It will be obvious that this arrangement will effect a great saving over the ordinary soda-water apparatus 90 and also will be much easier and convenient in operation. The pipe *b* may be coiled in the bottom of the casing *a*, and this casing, being filled with ice, will refrigerate the water, thus taking it to the charging devices at a low temperature and facilitating the absorption of the 95 gas.

Having thus described my invention, I claim as new and desire to secure by Letters Patent—

1. An apparatus for carbonating liquids, comprising a casing *a* reservoir in the casing, a mixing-chamber mounted on the reservoir communicating directly therewith, a dome

mounted on the mixing-chamber and communicating directly therewith, an injector-nozzle leading into the dome, a gas-supply pipe connected to the nozzle, a valve commanding the gas-supply pipe, a liquid-pipe leading into the dome transversely to the nozzle, and a valve commanding the liquid-pipe.

2. An apparatus for carbonating liquids, comprising a casing, a reservoir therein, means extending outside of the casing for withdrawing the liquid therefrom, a mixing-chamber mounted on and directly communicating with the upper part of the reservoir and within the casing, a dome on the mixing-chamber and communicating directly therewith, an injector-nozzle leading into the dome, a gas-supply pipe connected to the nozzle, a valve commanding the gas-pipe, a water-pipe coiled in the casing and leading to the dome transversely of the injector-nozzle, and a valve commanding the water-pipe.

3. An apparatus for carbonating liquids, comprising a reservoir having a perforated top portion, a mixing-chamber mounted on the reservoir at the perforated part thereof, said perforated part of the reservoir constituting the bottom of the mixing-chamber, a dome mounted on the mixing-chamber and communicating directly therewith, an injector-nozzle leading into the dome, a valve-controlled

gas-supply communicating with the nozzle, and a valve-controlled liquid-supply communicating with the dome.

4. An apparatus for carbonating liquids, consisting of a casing, a reservoir in the casing and provided with a pipe leading therefrom out through the casing, said pipe being provided with a cock, a mixing-chamber on the top of the reservoir and communicating therewith, a dome on the mixing-chamber, an injector in the dome, a valve-casing in the inclosing casing and connected with the injector, a valve in the casing and having its stem leading out through the inclosing casing, a gas-supply connected with the valve-casing, a second valve-casing in the inclosing casing and connected with the upper part of the dome, a valve in the said casing and having its stem extending out through the inclosing casing, and a water-supply pipe coiled in the inclosing casing and connected with the valve-casing, substantially as described.

In testimony whereof I have signed my name to this specification in the presence of two subscribing witnesses.

CHARLES A. WILKINSON.
